UNITED STATES PATENT OFFICE.

EVERETT B. PRESTON, OF CHICAGO, ILLINOIS.

DESIGN FOR A RUBBER SHOE.

SPECIFICATION forming part of Design No. 14,774, dated February 19, 1884.

Application filed September 18, 1883. Term of patent 7 years.

To all whom it may concern:

Be it known that I, EVERETT B. PRESTON, a citizen of the United States, residing in Chicago, in the county of Cook and State of Illinois, have invented and produced a new and useful Design for Rubber Boots and Shoes, of which the following is a specification.

My design relates to the ornamentation of the uppers of rubber boots and shoes, and is illustrated in the accompanying drawing forming a part of this specification.

In said drawing, which is a perspective view of a rubber shoe to which my design has been applied, *a* represents a raised rib extending from the toe to the ankle in a straight line

along the center of the upper. This rib is wide and flat upon its upper surface.

Similar ribs, *b*, extend from this center rib down to the sole of the boot or shoe upon either side, and in a direction inclined toward the heel.

I claim—

The design for a rubber boot or shoe upper, consisting of the raised central rib, *a*, and the lateral ribs *b*, substantially as shown and described.

EVERETT B. PRESTON.
